Attorney,

UNITED STATES PATENT OFFICE.

LACY LOUIS TAPP, OF ELKTON, KENTUCKY.

CATTLE-GUARD.

1,155,968.

Specification of Letters Patent.

Patented Oct. 5, 1915.

Application filed May 24, 1915. Serial No. 30,220.

To all whom it may concern:

Be it known that I, LACY L. TAPP, a citizen of the United States, residing at Elkton, in the county of Todd and State of Kentucky, have invented new and useful Improvements in Cattle-Guards, of which the following is a specification.

The present invention relates to cattle guards for use adjacent railway tracks, the same being in a position adjacent the track where it automatically assumes a position above the track to prevent animals from traveling along the track past the gate, but which will also be automatically operated by a passing train to swing the gates to the opposite sides of the track.

A further object of the invention is generally to improve this class of devices so as to increase their utility, durability and efficiency.

With the above and other objects in view, the improvement resides in the construction, combination and arrangement of parts set forth in the following specification and falling within the scope of the appended claims.

In the drawings: Figure 1 is a perspective view of a device constructed in accordance with the present invention, the gates being shown in their normal closed position across a railway track, Fig. 2 is a plan view illustrating the gates in their open position to permit of the passage of a train therebetween, Fig. 3 is a perspective view of the rail contact member, Fig. 4 is a perspective view of the turning shaft, and Fig. 5 is a sectional view illustrating the manner in which one of the arms comprising the gate is secured to the gate pivot to actuate the remaining arm, Fig. 6 is a transverse sectional view approximately on the line 6—6 of Fig. 2 and looking in the direction of the arrows, Fig. 7 is an enlarged sectional view approximately on the line 7—7 of Fig. 2.

Referring now to the drawings in detail, 1 designates a plurality of ties which support rails 2 of a track. Secured upon two of the ties to the opposite side of each of the rails 2 are blocks 3, the same having 50 their inner faces preferably shaped to be received within the fishing spaces of the rail, and the same being also provided with angular extensions through which pass the securing spikes 4. Pivoted to each of the blocks 3 is a longitudinally extending contact member 5. The members upon each of

the outer sides of the rails have their free ends disposed toward each other, and each of the contact members 5 is constructed from a substantially rectangular piece of 60 suitable metal, the pivotal end of which being reduced, but each of said members has its upper face gradually inclined upwardly to its free end, so that a portion of the contact member will at all times be 65 normally sustained above the tread of the rails in a manner which will be presently set forth. Each of the members 5 has upon its outer face and at its lower edge a lateral extension or enlargement 7, each of the 70 said portions 7 being provided with a longitudinally extending cross sectionally round lug 8.

Arranged to the outer side of each of the rails 2 between each pair of members 5 is a 75 longitudinally extending shaft 9; each of said shafts having its opposite ends provided with right angular offset portions 10, and each of the said portions is provided with an opening forming a bearing for the 80 longitudinally extending lugs 8 of each pair of contact members 5. The shaft 9 is journaled in bearings provided by brackets 11 which are secured to certain of the ties 1 as well as to the outer sides of the rails, 85 and each shaft 9 is approximately centrally formed with an enlarged portion 12 provided with a pair of spaced ears 13—13, the ears being disposed at a right angle to the angular ends or members 10 of each of the 90 shafts. Passing through each pair of ears upon each of the shafts 9 is a pivot member 14, and arranged upon the said pivot is a plurality of arms 15—15. One of the arms, preferably the central arm which, for 95 distinction, is indicated by the numeral 16, is rigidly secured to the pivot 13, as indicated by the numeral 17, and the said pivot 14 is also fixedly secured within its bearings in the ears 13—13. Flexible elements 100 18 connect the arms 15 with each other and with the arm 16, so that when the members are spread they will radiate from the pivot 14 while the flexible members 18 secured to the rigid arms 16 as well as to the 105 movable arm will limit the swinging movement of the said arms. The arm 16 is normally sustained approximately vertical when the gate is closed so that the members comprising the gate will swing or tilt both 110 across the track and toward the fence 20.

It is to be noted that when a train moving

upon the track toward the gate from either direction, one of the contact members 5 will be engaged by the tread of the wheels and depressed, thus rotating the shafts 9 in opposite directions bringing the ears at an outward angle with relation to the track. The arm 16 having moved beyond its vertical position will, through the medium of the flexible connections 18 throw the arms 10 arranged over the track toward the ends of the fence 20 which, as shown in the drawings, is arranged at the opposite sides of the gate and which divides two fields or pastures. It will be also noted that one of the wheels of the rolling stock is constantly in engagement with one of the contact members 5 until after the train has entirely passed the gate, so the weighted throw means cannot operate until the entire train 15 has passed the outer throw members. To return the gate to its normal closed position, I have arranged upon each of the shafts 9 a finger 21 disposed at a right angle to the ears 13, and I have arranged posts or standards 22 adjacent the said fingers. Each of the posts is provided with a pivoted member 23 having its outer end provided with a weight 24 and its inner end provided with a flexible member 25 which is secured to the 20 finger 21. The weight will, of course, automatically swing the member or beam 23 and the same will, through the medium of a flexible member 25, again swing the shaft 9 so as to bring each of the gates to its 25 closing position across the track.

If desired the shafts 9, to the opposite sides of the ears 13 may be provided with arms 26, the same being arranged parallel with the ears 13, and each of said arms 26 30 is provided with a flexible member 27 which connects with the end arm or bar 15 of the gate, this means adding to the strength and rigidity of the gate structure.

From the above description, taken in connection with the accompanying drawings, the simplicity of the device, as well as the advantages thereof will, it is thought, be perfectly apparent to those skilled in the art to which such invention appertains 40 without further detailed description.

Having thus described the invention, what I claim is:

1. In a cattle guard for railway rails, substantially rectangular contact members arranged in pairs to the opposite sides of the rails, blocks connected with the rails and 50

receiving pivots at the outer end of each of the contacts, each of said contacts having its outer face at its inner end formed with an enlargement provided with a longitudinally extending lug, a shaft journaled in bearings arranged between each pair of contact members, each of said shafts having angular ends providing bearings for the lugs of the contact members, a post central of each of the shafts, a member centrally pivoted to the post, a weight upon the outer end of the said member, a connection between the said member and each of the shafts, ears arranged at a right angle to the angular ends 60 of the shafts and disposed centrally of each of the shafts, a swinging gate comprising a plurality of arms pivotally secured between the ears, one of said arms being connected with the pivot, and a flexible connection between the last mentioned arm and the remaining arms of the gate.

2. In a cattle guard for railway rails, substantially rectangular contact members arranged in pairs to the opposite sides of the rails, blocks connected with the rails and receiving pivots at the outer end of each of the contacts, each of said contacts having its outer face at its inner end formed with an enlargement provided with a longitudinally extending lug, a shaft journaled in bearings arranged between each pair of contact members, each of said shafts having angular ends providing bearings for the lugs of the contact members, a post central of each of the shafts, a member centrally pivoted to the post, a weight upon the outer end of the said member, a connection between the said member and each of the shafts, ears arranged at a right angle to the angular ends 70 of the shafts and disposed centrally of each of the shafts, a swinging gate comprising a plurality of arms pivotally secured between the ears, one of said arms being connected with the pivot, and a flexible connection between the last mentioned arm and the remaining arms of the gate.

3. In testimony whereof I affix my signature in presence of two witnesses.

LACY LOUIS TAPP.
